UNITED STATES PATENT OFFICE.

WILLIAM HOWARD WINSWORTH, OF YOUNGSTOWN, OHIO, ASSIGNOR TO THE COLUMBUS RAILWAY SUPPLY COMPANY, OF COLUMBUS, OHIO, A CORPORATION OF OHIO.

RAIL-ANCHOR.

1,060,728.

Specification of Letters Patent.

Patented May 6, 1913.

Application filed June 24, 1912. Serial No. 705,626.

To all whom it may concern:

Be it known that I, WILLIAM H. WINSWORTH, a citizen of the United States, residing at Youngstown, Ohio, have invented a certain new and useful Improvement in Rail-Anchors, of which the following is a full, clear, and exact description, such as will enable others skilled in the art to which it appertains to make and use the same.

10 This invention relates to rail anchors such as are used in railway track structures for preventing longitudinal movement or creepage of the rails.

One object of my invention is to provide 15 a device of the character described which comprises a rail-gripping member that is wedged tightly between the head and the base flange of the rail.

Another object is to provide a rail anchor 20 of the character above-referred to which is so designed that it will effectively prevent longitudinal movement or creepage of a rail without nicking or otherwise mutilating the rail. And still another object is to provide 25 an inexpensive rail anchor or anti-creeping device that can be applied and removed easily and which is so designed that slight variations in the cross-sectional dimensions of a rail will not prevent the device from 30 gripping the rail tightly.

Other objects and desirable features of my invention will be hereinafter pointed out.

Figure 1 of the drawings is a cross sectional view of a rail showing one of my improved anchors arranged in operative position; Fig. 2 is a side elevational view of the rail and anchor; and Fig. 3 is a top plan view.

Referring to the drawings which illustrate the preferred form of my invention, A designates an ordinary T-rail that rests upon a tie B. My improved rail anchor consists of a tie-engaging member C that extends transversely under the base flange 40 of the rail and bears against one side of the tie, and a rail-gripping member D wedged tightly between the head and the base flange of the rail and secured to the tie-engaging member C in such a manner that it cannot 45 move relatively to same and thus release the rail. The tie-engaging member C is provided at one end with a hook-shaped portion 1 that laps over one edge of the base flange of the rail and at its opposite end 50 with a portion 2 that projects upwardly

above the base flange of the rail, as shown in Fig. 1. The rail-gripping member D consists of an approximately wedge-shaped device arranged vertically and provided at its upper and lower ends with oppositely inclined or beveled surfaces 3 and 4 that bear against the under side of the head of the rail and against the top face of the base flange of the rail, respectively, said member D being so proportioned that it does not bear against the web of the rail. The member D is provided at its lower end with an integral laterally projecting portion 5 that fits in a horizontally disposed groove or guideway 6 in the upwardly projecting portion on the tie-engaging member C, and in the embodiment of my invention herein shown the coöperating outer edge of the portion 5 and the inner wall of the guideway 6 are inclined or tapered longitudinally of the rail, as shown in broken lines in Fig. 3, so that the laterally projecting portion 5 on the lower end of the rail-gripping member will act as a wedge to draw both the members C and D into intimate engagement with the rail. I do not wish it to be understood, however, that my invention is limited to the exact construction herein shown for, if desired, other means such, for example, as a separate wedge, could be arranged between the coöperating portions 2 and 5 of the members C and D for causing said members to grip the rail tightly.

To arrange the anchor in position, the tie-engaging member C is first passed under the rail so that the hook-shaped portion 1 on same will engage one edge of the base flange of the rail and the rail-gripping member D is thereafter inserted between the head and base flange of the rail and moved longitudinally of the rail so as to cause the laterally projecting portion 5 on the lower end of same to enter the guideway 6 in the upwardly projecting portion 2 on the member C. As the member D is being driven longitudinally into operative position, the wedge-shaped portion 5 on the lower end of same causes said member to move inwardly toward the rail and thus become wedged tightly between the head and the base flange of the rail and also causes the member C to move transversely in the opposite direction, thereby forcing the hook-shaped portion 1 on the member C tightly against the opposite edge portion of the base flange of the

5 rail. In order to eliminate the possibility of the member D working loose and thus releasing the rail I have provided means for securely locking the member D in operative position. The means herein shown for accomplishing this consists of a lip 7 on the upwardly projecting portion 2 of the member C that is adapted to be bent downwardly over the wide end of the wedge-shaped portion 5 of the rail-gripping member D, as shown in broken lines in Fig. 2, after said member has been driven into operative position. To remove the anchor it is only necessary to bend up the locking lip 7 and then 10 drive the rail-gripping member D in the reverse direction out of engagement with the rail and the portion of the member C with which it coöperates.

15 The members C and D can be cast, forged or pressed from sheet steel of sufficient strength to withstand the strains which the anchor is subjected to, when in service, and as the device is composed of only two parts of simple design that do not require any 20 machining, the anchor can be manufactured at a very low cost. Such a rail anchor can be applied and removed easily, and as it has a relatively great area of gripping surface on the rail it will effectively hold the 25 rail and prevent it from creeping or moving 30 longitudinally.

35 In addition to the desirable features above-mentioned, my improved anchor will not scar or nick the rail and thus weaken the rail, owing to the fact that the means which locks the tie-engaging member of the anchor to the rail consists of a gripping member of relatively great area or bearing surface that is wedged tightly between the under 40 side of the head of the rail and the top face of the base flange of the rail. Furthermore, slight inequalities or variations in the cross sectional dimensions of a rail do not prevent my improved anchor from clamping the rail 45 tightly because the tie-engaging member is constructed to receive the base flange of the rail freely, and the means which binds said member to the base flange of the rail consists of a member having two wedge-shaped portions one of which bears against the under 50 side of the head and against the top face of the base flange of the rail without contacting with the vertical web of the rail, and the other coöperating with a tapered guideway 55 in the tie-engaging member that lies in a higher horizontal plane than the base flange of the rail.

60 When the anchor is formed from cast metal as herein shown, the rail-gripping member D is preferably provided with marginal ribs 8 so as to reinforce and strengthen the vertically disposed portion of same, and the tie-engaging member C is also provided with reinforcing ribs or flanges 9.

65 Having thus described my invention, what

I claim as new and desire to secure by Letters Patent is:

1. A rail anchor comprising a tie-engaging member having a portion that laps over one edge of the base flange of the rail, a rail-gripping member wedged between the head and the base flange of the rail but not touching the web and having a portion which projects under an overlapping portion on said tie-engaging member, means for causing said members to be drawn tightly into intimate engagement with the rail when said rail-gripping member is being moved into operative position, and means on one of said members for locking the rail-gripping member in position. 70 75 80

2. A rail anchor comprising a tie-engaging member extending transversely under the base flange of the rail and provided at one end with a portion that laps over said base flange, an upwardly projecting portion on the opposite end of said member provided with a guideway that lies in a higher horizontal plane than the bottom face of the base flange of the rail, a rail-gripping member having a laterally projecting portion that fits in said guideway and a vertically disposed portion that is wedged tightly between the head and the base flange of the rail but does not bear against the web of the rail, and means on one of said members that is adapted to be bent into such a position that said rail-gripping member cannot move out of engagement with the rail. 85 90 95

3. A rail anchor comprising a tie-engaging member arranged transversely under the rail and provided at one end with a portion for engaging the base flange of the rail and at its opposite end with a portion in which a horizontally disposed guideway is formed 100 at a point above the surface on which the base flange of the rail rests, a rail-gripping member having a substantially wedge-shaped portion that is wedged tightly between the head and the base flange of the 105 rail, and a laterally projecting wedge-shaped portion on said rail-gripping member that lies in said guideway. 110

4. A rail anchor comprising a tie-engaging member that is adapted to be arranged 115 transversely under a rail, a hook-shaped portion on one end of said member for engaging one edge of the base flange of the rail, an upwardly projecting portion on the opposite end of said member having a horizontally disposed tapered guideway formed therein, a rail-gripping member having a wedge-shaped portion that fits between the head and the base flange of the rail and an integral laterally projecting tapered portion 120 that fits in said guideway, and a lip on said tie-engaging member that is adapted to be bent down over the end of the laterally projecting portion on said rail-gripping member to retain it in operative position. 125 130

5. A rail anchor comprising a tie-engaging member provided at one end with means for receiving one edge of the base flange of a rail, a rail-gripping member arranged on 5 the opposite side of the rail and having a portion that is wedged tightly between the under side of the head and the top face of the base flange of the rail, interlocking portions on said rail-gripping member and tie-engaging member constructed in such a manner that both of said members will be drawn 10 into intimate engagement with the rail when

the rail-gripping member is being driven into operative position, and an integral part on one of said members that is adapted to be bent into such a position that it prevents displacement of said rail-gripping member.

In testimony whereof I hereunto affix my signature in the presence of two witnesses, this 11th day of June 1912.

WILLIAM HOWARD WINSWORTH.
